UNITED STATES PATENT OFFICE.

LOUIS H. C. TOEDT, OF BROOKLYN, NEW YORK.

DESIGN FOR A GLOBE FOR WATER-FILTERS.

43,835.

Specification for Design. Patented Apr. 8, 1913.

Application filed May 29, 1912. Serial No. 700,519. Term of patent 7 years.

To all whom it may concern:

Be it known that I, LOUIS H. C. TOEDT, a subject of the Emperor of Germany, residing at Brooklyn, in the county of Kings and State of New York, have invented a new, original, and ornamental Design for a Globe for Water-Filters, of which the following is a specification, reference being had to the accompanying drawing, forming part thereof, in which the figure is an elevation

of a globe for water-filters showing my new design.

I claim:

The ornamental design for a globe for water-filters as shown.

LOUIS H. C. TOEDT.
